FLY TRAP

Gregory Daratsos, Flushing, N.Y., assignor to Dars Met-
All Industries, Inc., Long Island City, N.Y.

Filed June 13, 1973, Ser. No. 369,568

Term of patent 14 years

Int. Cl. D22—06

U.S. Cl. D22—19

FIG. 1 is a bottom perspective view of the fly trap;
FIG. 2 is the bottom view of the design; and
FIG. 3 is a view taken along lines 3—3 of FIG. 2 of the design.

The strings have been omitted from FIG. 3 for convenience of illustration.

I claim:

The ornamental design for a fly trap, as shown and described.
